UNITED STATES PATENT OFFICE.

WILLIAM A. LORENZ, OF HARTFORD, CONNECTICUT.

HERMETIC CLOSURE FOR RECEPTACLES.

No. 841,027.

Specification of Letters Patent.

Patented Jan. 8, 1907.

Application filed April 11, 1904. Serial No. 202,502.

To all whom it may concern:

Be it known that I, WILLIAM A. LORENZ, a citizen of the United States, and a resident of Hartford, in the county of Hartford and State of Connecticut, have invented certain new and useful Improvements in Hermetic Closures for Receptacles, of which the following is a full, clear, and exact specification.

This invention relates to closures for hermetically-sealed jars and other receptacles.

Figures 1 and 2 are fragmentary side views of a jar with its gasket and cap, Fig. 1 showing the parts in their exhausting or air-ex-pelling position, and Fig. 2 showing the cap pushed down to its sealed position. Fig. 3 is a side view of a sealed jar. Fig. 4 is a fragmentary side view of a sealed jar, showing a modified form of the closure. Fig. 5 is a diagram showing the effect of tilting action by the cap.

In the hermetic sealing of jars and other receptacles by means of a gasket and compressing-cap therefor the type of closure commonly employed is that which is known as a "wedging closure," in which the sealing pressure is applied to the gasket at an angle with the direction in which the cap moves while effecting the seal as compared with a closure in which the gasket is compressed directly against a flat seat, which is at right angles with the direction of movement of the cap. This wedging action is usually obtained by providing the receptacle or the cap, or both, with a tapering or flaring seat for the gasket.

The superiority of this type of closure is due largely to the fact that the actual and effective sealing pressure upon the gasket obtained by these tapering or flaring surfaces is greater than the direct or initial pressure upon the cap, this effective pressure increasing as the taper or angle of the pressing-surfaces approaches a parallel relation to the direction of movement of the cap. On the other hand, the more nearly the pressing-surfaces approach a parallel relation to the direction of movement of the cap the greater the difficulty of maintaining the cap in a level position upon the gasket, not only during the exhausting and sealing operation, but also in the subsequent handling or transportation of the sealed packages. The more nearly parallel the two opposite sides of the compressing taper or angle are with each other the more readily the cap and gasket may be displaced relative to each other and to the jar, so that the cap will tip down on one side and up on

the other whenever there is any unevenness of pressure exerted upon it, such as is liable to occur during the handling and piling up, which takes place between the filling and the sealing of the jar and its delivery to its ultimate purchaser. This tipping of the cap is objectionable, not only because it detracts from the appearance of the package, but also for the more important reason that the two sealing-seats of the cap and gasket are thereby moved out of their intended conformity with each other and with the gasket. In the modern development of this art the gasket and its sealing-seats upon the receptacle and the cap are carefully designed, arranged, and proportioned to coöperate in a particular and exact relation and conformity, any departure from which endangers the integrity or permanence of the seal.

In the wedging closures hitherto commonly employed the tapering compressing-surfaces are usually formed at a considerable angle to the direction of the sealing movement of the cap, this angle being a sort of compromise intended to secure the greatest amount of effective sealing pressure consistent with affording a reasonably stable angle for supporting the cap in a level position; but this compromise angle precludes the more effective pressure which might be obtained by making the taper or angle of the compressing-surfaces more nearly parallel with the direction of movement of the cap. To compensate, in a measure for this sacrifice of the more effective sealing angle, some of these closures have been hitherto designed and arranged so as to concentrate the sealing pressure upon a single comparatively narrow zone of the gasket instead of distributing the pressure over a relatively greater area, and thereby lessening the pressure per unit of area.

In the present invention the sealing pressure is divided between two different zones and upon what are practically two different sealing-seats, each of which is tapered at the most advantageous angle for the efficiency of the wedging pressure without regard to the function of leveling the cap, the latter function being attended to by separating the two sealing zones or seats, so as to afford an extended base of support for the cap. Moreover, the effective sealing pressure thus gained by the relatively slight taper of the sealing-seats compensates wholly or in part for the apparent sacrifice of sealing pressure

due to dividing it between the two sealing-seats. For example, by employing a taper which is one-half the angle of the former taper the effective pressure is approximately 5 doubled, thus enabling it to be divided between its two sealing-seats without real loss, the effective pressure on each seat being equal to the pressure which in the other instance was exerted upon a single seat.

10 Thus the present invention may be properly denominated a double closure in two senses: first, in the sense that the effective sealing pressure may be doubled, and, secondly, in the respect that two practically independent sealed joints are formed. It is 15 obvious that such a double closure, in which the gasket is compressed on any two circumferential zones, instead of one, and with the same pressure on each zone as used heretofore on a single zone, would be very much more reliable than the ordinary single closure, as it would require the failure of two joints instead of a single joint to cause leakage.

20 The stability of position of the cap due to the separation of the two sealing zones or seats is also increased by making the lower sealing-seat of greater diameter than the upper seat and by providing what is herein 25 designated a "leveling-seat" for the gasket and cap intermediate the two sealing zones. That leveling-seat is disposed at a greater angle than the sealing-seats and cooperates with some portion of the gasket to prevent 30 undue tipping of the cap, particularly when the latter is in its sealed position.

The jar 16 in Figs. 1 and 2 has a neck 17, which tapers slightly outward toward the bottom of the jar and which forms the uppermost of the two sealing zones. Below 35 it is another tapering portion 18, which forms a receiving-seat upon which the gasket is supported against the downward pressure of the cap. The portion 18 of the jar terminates in a rounded or chamfered shoulder or zone 19, which forms the second sealing zone of the jar. The cap 22 is provided in its upper portion with a shoulder 23 and a flaring portion 24, joined by an intermediate 40 portion 25. The gasket 27 is preferably of a rhombic or rhomboidal cross-section, though it may be of any suitable shape. The gasket is supported on the receiving-seat 18 with one thin edge 28 extending upward along the upper sealing zone 17, while 45 its other thin edge 29 extends downwardly over and beyond the lower shoulder 19. In this position the cap rests on the gasket so as to have an annular space between the intermediate portion 25 of the cap and the adjacent neck of the jar. As the cap 22 moves downward under the pressure of the sealing operation the shoulder 23 compresses the upper part of the gasket against the 50 upper tapering neck 17 of the jar, while

the flaring portion 24 of the cap compresses the lower part of the gasket against the shoulder 19 of the jar. As the angles of the two sealing-surfaces 17 and 24 of the jar and cap, respectively, diverge only slightly from 55 the vertical line of the sealing movement on the cap, the gasket is pinched along the two sealing zones *a* and *b*, Fig. 2, with a very high degree of pressure. The annular space between the intermediate portion 25 of the 60 cap and the jar-neck admits the central portion of the gasket 27, Fig. 2, so that the compression of the gasket at that portion is less than at the sealed joints. The body of the gasket thus supports the cap from being displaced, on account of the greater angle of the surfaces 18 and 25, and because the gasket is less compressed at its center the cap can settle downward readily against the gasket at the zones *a* and *b*, as the continued 65 pressure on the cap may cause it to do so.

On account of the degree of separation between the two sealing zones any tipping of the cap will cause an additional compression of the gasket at one or more points on the 70 sealing zone several times greater than the same amount of tipping would cause if there were but one zone. In the latter case the axis of the tipping movement would locate itself in the plane of the sealing zone, since 75 that location would cause the least amount of movement in the cap against the gasket and would therefore meet with the least amount of resistance; but in the case of two zones the axis would locate itself somewhere 80 between those two zones, since the resistance on any given zone increases the farther the axis of the tipping movement is from the zone. This may be clearly seen by reference to the diagram, Fig. 5, in which 44 85 and 45 represent the planes of the two sealing zones, 48 and 49 the tapering sealing-surfaces, and 46 the axis of the tipping movement. If the cap tips downward on the left, that part 90 of it which is compressing the gasket hardest 95 on that side must move substantially in the line of the arc 47 and must therefore move inward against the gasket in the line of the greatest resistance much faster than if the axis of tipping movement were in the plane 100 of the sealing zone 49.

In Fig. 4 is shown a closure in which the jar 34 has two tapering surfaces 35 and 36 and the cap 38 two compressing-shoulders 39 and 40 for pinching the gasket 42.

105 The form of gasket is not an essential feature of the present invention, since it may be varied in ways which will be obvious to those familiar with this art. Instead of a single relatively wide gasket two or more 110 gaskets may be employed, using a separate gasket for each of the sealing zones, either with or without an intermediate leveling-gasket. Thus in various ways, which will be 115 apparent to those familiar with this art, the 120 125 130

invention herein shown may be modified and extended.

I claim as my invention—

1. The combination with a receptacle, of a closure therefor, comprising gasket material, and a cap provided with two sealing zones for wedging the gasket material against two different zones of the receptacle, to establish two separated circles of contact, having 10 a greater pressure than at the other portions of the gasket.
2. The combination with a receptacle, of a hermetic closure therefor comprising gasket material, and a cap having a plurality of annular zones, each inclined at an angle with 15 the direction of the sealing movement of the cap for forming a plurality of wedging-closure joints upon the receptacle.
3. The combination of a receptacle provided with a plurality of annular sealing zones, gasket material therefor, and a cap provided with means for compressing the gasket material at an angle against each of the sealing zones of the receptacle, to establish 20 25 the sealing pressure at two separated circles of hardest contact.
4. The combination with a receptacle provided with a plurality of annular tapering sealing zones, gasket material therefor, and a cap provided with means for compressing the gasket material at an angle against each of the said sealing zones of the receptacle, to divide the sealing pressure, and establish it at two separated circles of contact.
5. The combination of a receptacle provided with two separated tapering sealing zones of different diameters, compressible gasket material therefor, and a cap provided with means for compressing the gasket material at an angle against each of the sealing zones of the receptacle to form two wedging-closure joints.
6. The combination with a gasket, of a receptacle having two sealing zones, a flaring cap having two sealing zones for wedging the gasket against the two sealing zones of the receptacle, leaving an intermediate annular space substantially filled by the gasket between the two sealed joints, to divide the

pressure and establish it at two separated 50 circles of hardest contact.

7. The combination with a gasket, of a receptacle having two sealing zones, an intermediate receiving-seat for the gasket, and a flaring cap having two sealing zones for 55 wedging the gasket against the two sealing zones of the receptacle, to divide the sealing pressure and establish it at two separated circles of hardest contact.

8. The combination with a gasket, of a receptacle having two separate sealing zones, intermediate receiving-seat for the gasket, a flaring cap having two sealing zones, and an intermediate portion between the two zones diverging from the intermediate seat of the 60 receptacle, whereby the gasket is compressed at the two sealing zones with greater pressure than at the intermediate portion of the gasket.

9. The combination of a receptacle provided with a rounded shoulder and with a tapering portion, forming two circumferential sealing zones, gasket material therefor, and a cap provided with a tapering portion and with a rounded shoulder for wedging the 65 gasket against the aforesaid sealing zones of the receptacle, to establish increased pressure at two separated circular joints of the closure.

10. The combination of a receptacle provided with a tapering circumferential zone, and a circumferential shoulder below the said zone, gasket material therefor, and a cap provided with a circumferential shoulder, and with a tapering circumferential zone for 80 85 compressing the gasket material against the tapering zone, and the shoulder, respectively, of the receptacle, to form two separated sealing-joints, each having a higher degree of pressure than the remaining portions of 90 the gasket material.

In testimony whereof I have signed my name to this specification in the presence of two subscribing witnesses.

WILLIAM A. LORENZ.
